Patented Aug. 12, 1919.

UNITED STATES PATENT OFFICE.

ASHMEAD B. CHESTER, OF JACKSONVILLE, ILLINOIS.

DIESTOCK.

1,312,949.

Specification of Letters Patent. Patented Aug. 12, 1919.

Application filed May 16, 1918. Serial No. 234,932.

To all whom it may concern:

Be it known that I, ASHMEAD B. CHESTER, a citizen of the United States, residing at Jacksonville, in the county of Morgan and

5 State of Illinois, have invented certain new and useful Improvements in Diestocks, of which the following is a specification.

This invention relates to tools, and more especially to pipe and rod cutters; and the 10 object of the same is to produce a stock or handle adapted for receiving dies by which threads may be cut onto rods or pipes, or for receiving a cutting tool such as a wheel mounted within a block.

15 The invention relates particularly to the stock or handle by which the various instrumentalities are carried, and the details of its construction are set forth in the following specification and claim, and shown in the 20 drawings, wherein:

Figure 1 is a plan view,

Fig. 2 a longitudinal section on the line 2—2 of Fig. 1, and

Fig. 3 a cross section on the line 3—3.

25 Fig. 4 is a detail of the hinge.

The stock as a whole is made up of a long body having two handles, or hand pieces 1 and 2 attached to the extremities of said body by any suitable means. Usually these 30 handles are screwed into the body of a tool of this character, and when unscrewed the parts can be stored in small compass. The body itself is made in two complementary U-shaped elements 3 and 4 with their open

35 ends adjacent each other, hingedly connected at the point 5 about mid-way the length of the body and at one side of the central opening 6. Directly opposite the hinge one element carries ears 7 and the

40 other has a single ear projecting between these ears, and a pin or bolt 8 extends through aligned openings in all ears to hold the parts detachably connected. Both elements have rather narrow fins 9 standing

45 in a single plane, and other fins 10 at the ends of the opening 6 standing in a plane at right angles to the fins 9 so as to give great strength to the structure. Along each side of the opening is a transverse web 11 which,

50 with the adjacent fin makes each side of the element have the construction of a letter T. Along each edge of the web is a flange 12, the two flanges at one side of the opening projecting toward and standing opposite the 55 two flanges at the other side. These flanges extend along the full length of both webs 11,

connect with each other directly across one end of the opening, as at 13, and are also carried around the other end of the opening as shown at the right of Fig. 1. At this 60 point the webs 11 connect with each other in an angle as indicated at 14, and the flanges 12 may or may not be present along the inner faces of the angle. The latter is braced by both fins 9 and 10. With the exception that 65 the entire body is made in two elements 3 and 4, all parts thus far described are formed of one piece of metal and the handles applied later.

Slidably mounted in the trackways 70 formed by the webs and flanges of one element such as that numbered 4, is herein shown a block 20 in which is pivotally mounted a cutter wheel 21, its cutting edge standing adjacent the angle 14 at the right 75 end of the opening 6. Slidably mounted in the same trackways are dies, herein numbered 22 and 23 and shown as having complementary notches by means of which a thread may be cut onto a pipe or rod. There 80 may be and doubtless will be other dies employed, and they may be selectively inserted when the bolt is removed and the two elements 3 and 4 turned on their hinge 5. The dies 22 and 23 and others like them may be 85 employed to hold the block 20 near the angular end 13 of the recess 6, so that the cutter 21 will coat with said end when the tool is in use.

Mounted in the other element 3 is the adjusting mechanism. This element may have its body cast to form an elongated nut 30 into whose threaded bore engages a screw 31 whose head 32 stands toward the center of the opening and may have flat faces or 95 sockets for the insertion of a pin or spanner wrench by means of which the screw may be turned. This head as seen in the drawings, is preferably round on its exterior and of a size to rotate between the webs and 100 flanges but a little too large to be slipped therefrom, except when the screw is withdrawn longitudinally as will be clear. In Figs. 1 and 2 I have shown other nuts 34 and 35 mounted on the threads of the screw, 105 the nut 34 being square and the nut 35 round as shown in Fig. 1. The square nut is of such size that it may be inserted between the flanges 12 at the point where they are cut away, but may not then rotate between such flanges. The other nut 35 is of 110 such size that it may be turned between the

flanges and webs, and therefore it constitutes a jam nut to be run down onto the square nut after the parts are set. When these additional nuts are employed their 5 obvious purpose is to cause the screw to operate near the center of the device for holding the dies and other blocks in place, because without the nuts the threaded end of the screw would have to run down into the 10 integral nut 30 for sufficient distance to give the threads a strong engagement. In the same manner, when the cutter element is employed there will have to be a number of dies or other blocks between the head of the 15 screw and the block 20, so as to hold the latter toward the angular end of the opening 6, because otherwise the screw would have to be long enough to perform that function without the interposition of any other 20 member.

The use of this stock is thought to be obvious from the above description. With the parts assembled as seen in Fig. 1, and perhaps with other blocks filling out the 25 space left blank in this view and in Fig. 2, when a pipe or rod is to be cut it is inserted through the opening 6 adjacent the angle 14, and the screw set to push the block 20 and cutter 21 toward the rod or pipe. Then 30 the entire device is revolved around this piece by hand, and step by step the cutter is advanced as usual. If the work is to be threaded it is passed between the threaded faces of the dies 22 and 23, and the threads 35 cut in a manner which will be clear. If other dies are needed the pin or bolt 8 is removed, the device opened on its hinge 5, and the dies herein shown replaced by others 40 which will go with the outfit and which will have a different thread.

The foregoing description and the drawings have reference to what may be considered the preferred, or approved form of my invention. It is to be understood that I may make such changes in construction and 45 arrangement and combination of parts, materials, dimensions, et cetera, as may prove expedient and fall within the scope of the appended claim.

Having thus fully described my invention, what I claim as new and desire to secure by Letters Patent, is:—

In a die stock, the combination with a loop-shaped body having handles at its extremities, its opening being bounded by transverse webs having flanges along their edges except at one end where the flanges are omitted, the webs extending across one end of the opening and making an angle at the other end thereof; of dies 55 slidably mounted in the runway formed by said webs and flanges at that end adjacent the angle, the body having a socket nut formed at the other end of said opening, a screw whose shank is threaded into said nut and whose 60 head is round and of a size to prevent lateral displacement from between the flanges, said head being provided with means whereby it may be turned, and nuts on the screw removably mounted between said flanged 70 webs, one nut being square and non-rotary between the webs, and the other nut being round and rotary, thus constituting a jam nut as described.

In testimony whereof I affix my signature 75 in presence of two witnesses.

ASHMEAD B. CHESTER.
